United States Patent Office.

THADDEUS FOWLER, OF SEYMOUR, ASSIGNOR TO THE UNITED STATES PIN COMPANY, OF NEW HAVEN, CONNECTICUT.

Letters Patent No. 75,540, dated March 17, 1868; antedated March 7, 1868.

IMPROVEMENT IN MACHINES FOR PAPERING PINS.

The Schedule referred to in these Letters Patent and making part of the same.

TO ALL WHOM IT MAY CONCERN:

Be it known that I, THADDEUS FOWLER, of Seymour, in the county of New Haven, and State of Connecticut, have invented, made, and applied to use, a certain new and useful Improvement in Pin-Sticking Machinery; and I do hereby declare the following to be a full, clear, and exact description of the said invention, reference being had to the annexed drawing, making part of this specification, wherein—

Figure 1 is a plan of my said machine.

Figure 2 is a vertical section of the same at the line $x\ x$.

Figure 3 is a vertical section of the said machine at the line $x'\ x'$.

Figure 4 is a sectional plan in larger size of the base of the conductors, showing the mode in which one line of pins is cut off from the others; and

Figure 5 is a similar view, showing how the lines of pins in the conductors are sustained, and the line that is cut off allowed to drop.

Similar marks of reference denote the same parts.

Heretofore difficulty has been experienced in pin-sticking machines from the pins becoming obstructed, in consequence of any slight crook or bend, and hence the further movements of the machine sometimes bend the pin much more and prevent the machine working.

The object of my invention is to separate a row of pins at a time from the ends of the conductors, and stick them in such a manner that any crooked pin or imperfect pin will not check or obstruct the operation of the machine, but will fall through.

My invention consists in a spring cut-off, formed of a series of points that pass in between the first and second pins of the rows of pins in the conductors, and hold up all but the first row, which is allowed to fall into the sticking-apparatus, consisting in a series of grooves in front of which is a spring-door that is swung down by the action of a rake that enters the grooves and forces the pins down through the paper, as it is in the crimping-jaws.

In the drawing, a is a frame carrying the mechanism; b is a series of conductors, formed in any usual manner, and supplied with pins in any known or convenient way. Below the ends of the conductors b is an inclined breast, c , having grooves in its surface formed between plates that extend down from the lower ends of the bars forming the conductors b , or in any other convenient manner, and at the lower end of this inclined grooved breast c is the stationary crimping-jaw d , the strip of paper e , into which the pins are stuck, passing in between the breast c and jaw d , and passing down to any feeding-device for drawing the paper along periodically. The moving crimping-jaw f is on an arm, f' , fitted to swing on the centre 1 , and is operated at the right time by the cam g on the shaft h , and drawn back by the spring 2 , or other convenient mechanism. Upon the upper edge of the jaw f is the door i , hinged at its lower edge, and thrown up by a spring, 3 , so as to close against the grooves in the inclined breast c , and prevent the pins falling out of said grooves as they are dropped, as hereafter specified. 4 is an inclined curved arm on the door i , that extends out beneath the rake k , and said rake k is formed with teeth corresponding to the grooves in the breast c , and is set upon slide-bars 5 , that are mortised near their lower ends to slide upon pins 6 , that project from a cross-bar, 15 , near the base of the arm f' . 7 7 are springs acting to draw the rake k up, and 8 8 are springs that act to draw the rake away from the breast c . 11 are cams on the shaft h , that act at the proper time to force the teeth of the rake k back into the grooves in the breast c , and pins 9 9 on these cams 11 , acting upon toe-pieces 10 on the bars 5 , draw down the rake, sticking the pins into the crimped paper. This movement of the rake swings back the door i into the position shown in fig. 2, and as the pins 9 clear the toes 10 , and the rake k is drawn up again by the springs 7 , the door i is turned up again by its spring 3 , and closed. A bar, n , is fitted to slide below the ends of the conductors b , and it is moved at the right time by the lever o and cam p . From this bar project cut-off hooks s s , seen in larger size in figs. 4 and 5. These occupy a horizontal groove across the ends of the conductors, a little below their upper surfaces. r is a stop-bar, fitted to be moved up to the lower ends of the conductors, or drawn down from the same by the action of the levers q , cams t , and springs 11 .

It will now be understood that when the spring cut-offs *s* stand in the position of fig. 4, the pins in the conductors rest against the edge of the bar *r*, and hang by their heads; the spring cut-offs are then moved, their points enter between the bodies of the pins in the first and second row, preventing the pins from coming down the conductors while the bar *r* is drawn back, and drops the lowest row of pins, and they fall against the plate *u*, and thence pass into the grooves in the inclined breast *c*. The reverse movements of the spring cut-offs *s* and bar *r* allow another row of pins to come into position to be cut off as aforesaid.

What I claim, and desire to secure by Letters Patent, is—

1. The pointed cut-offs *s*, applied at the lower ends of the conductors, in combination with the stop-bar *r*, substantially as and for the purposes set forth.
2. The grooved breast *c*, and spring-door *i*, in combination with the rake *k*, substantially as and for the purposes set forth.

In witness whereof, I have hereunto set my signature, this twenty-sixth day of April, A. D. 1867.

THADDEUS FOWLER.
